DESIGN FOR A HOUSING FOR REFRIGERATOR COILS

George K. Bently, Kendallville, Ind., assignor to
McCray Refrigerator Company, Kendallville,
Ind., a corporation of Indiana

Application October 4, 1946, Serial No. 133,756

Term of patent 14 years

(Cl. D67—3)

To all whom it may concern:

Be it known that I, George K. Bently, a citizen of the United States and resident of Kendallville, in the county of Noble and State of Indiana, have invented a new, original, and ornamental Design for a Housing for Refrigerator Coils, of which the following is a specification, reference being had to the accompanying drawing, forming a part thereof.

In the drawing, Fig. 1 is a perspective view of a housing for refrigerator coils, showing my new design; Fig. 2 is a top view thereof; and Fig. 3 is an elevation of one side thereof, both sides having the same appearance.

I claim:

The ornamental design for a housing for refrigerator coils, substantially as shown and described.
GEORGE K. BENTLY.
